UNITED STATES PATENT OFFICE.

ANTON J. KOPP, OF SAN FRANCISCO, CALIFORNIA.

CLAMP FOR SLIDING WINDOWS.

Application filed August 13, 1924. Serial No. 731,753.

To all whom it may concern:

Be it known that I, ANTON J. KOPP, a citizen of the United States, residing at San Francisco, in the county of San Francisco and State of California, have invented new and useful Improvements in Clamps for Sliding Windows, of which the following is a specification.

The present invention relates to improved means for holding sliding windows and like closures in the desired position into which such windows or closures may be moved, which means comprises a simply constructed, small, compact, inexpensive clamping device which serves as a guide as well as a clamp, is capable of being readily and easily incorporated with body structures of automobiles wherein sliding windows are employed or as easily installed in other structures employing sliding windows or closures.

One of the objects of the invention is to provide a clamp which comprises a base or body member having a fixed jaw and movable jaws, both of a novel construction to facilitate the reliable operation of the device as a clamp and as a guide.

A further object is to provide in a clamp of the character described a novel and efficient means for operating the movable jaws, which means is arranged in a simple and effective manner, is easy to make and inexpensive.

With the above mentioned and other objects in view, the invention consists in the novel construction and combination of parts hereinafter described, illustrated in the accompanying drawings, and set forth in the claims hereto appended, it being understood that various changes in the form, proportion, size and minor details of construction within the scope of the claims may be resorted to without departing from the spirit or sacrificing any of the advantages of the invention.

Referring to the drawings:

Fig. 1 represents a longitudinal sectional view of the clamp of the invention showing it mounted on a sill and a part of a window sliding through the clamp.

Fig. 2 represents an end elevation, being broken away and showing a part of the lock in section, also showing portions of sliding closures in the clamp and the jaws in clamping position, in dotted lines.

Fig. 3 represents a top plan view of the clamp.

Fig. 4 represents a perspective view of the clamp as when mounted in a sill member, part of which latter is shown.

The clamp of this invention in the embodiment shown in the accompanying drawings comprises a plate-like body portion 1 of a substantially H-shape, there being recesses 2 and 3 in opposite sides of the plate. Screw holes 4 are formed adjacent the other edges or sides of the body plate to provide for fastening the body in a sill member as shown at A, Figs. 1 and 4.

Extending lengthwise of the body and preferably formed integral therewith is an upstanding fixed jaw 5 which is reduced in thickness and tapered from its central portion to the ends thereof, said ends terminating short of opposite edges of the body plate. Slidably mounted on the body plate in the recesses 2 and 3 and on opposite sides of the jaw 5, are movable upright jaws 6 and 7. Each jaw has a downward extension 8 reduced twice to provide shoulders 9 and 10. This extension is inwardly offset and at its lower end is rounded. An arcuate flange-like member 11 is formed integral with the extension and extends inwardly from it. On the upper ends of the member 11 are lateral flanges 12 extending as continuations of the shoulders 10. On the inner side of the member 11 is an obliquely disposed rib or screw segment 13. A circular opening 14 is formed through the center of the extension 8 for reception of the operating screw 15.

The plate 1 is provided on its under side with depending flanges 16 extending at right angles to the jaw 5 and provided with lateral extensions 17 on the upper sides of which latter the shoulders 10 slidably engage, whereas the sides and the flanges 12 slide upon the inner sides of the flanges 16.

The screw 15 has a central annular rib 18 extending from opposite sides of which are right and left screw threads 19 and 20, which threads are adapted to cooperate with the thread segments 13 of the jaws 7 and 8.

The ends of the screw are squared as at 21 and project outwardly from the sides of the clamp. A handle 22 having a socket 23 at one end is fitted to either end of the screw, dependent on the position and manner of use of the clamp. A screw 24 holds

the handle in place. A groove 25 is formed in the under side of the plate 1 and receives the rib 18 on the screw. Extending from opposite sides of the groove 25 are depressions 26 which receive the screw 15.

These shoulders 9 engage the upper side of plate 1 and act as stop members or braces when severe strains or stresses are imposed on the jaws.

10 The clamp of this invention acts as an effective antirattling device for the windows as well as a guiding and holding or locking means. The construction of the clamp is such that an easy assembling and disassembling is made possible and a ready removal of worn or broken parts may be made with little or no trouble.

I claim:

1. A clamp for sliding closures comprising a jaw plate to be attached to a member along which said closures are slidable, a fixed upright jaw carried by the body plate on opposite sides of which closures are adapted to engage, movable jaws slidable on opposite sides of and towards and away from the fixed jaw, said plate having recesses therein in which portions of the jaws are slidably engaged, laterally extending arcuate flanges on the lower portions of the jaws, having angularly directed upper ends, and track members on the under side of the plate slidably supporting said angular upper ends, ribs on the upper sides of said arcuate flanges, a rotatable member supported in the lower portions of the jaws and having right and left hand screw threads

thereon engaging the said ribs, said member having its ends projecting outwardly beyond the outside of said movable jaws, an annular rib on said rotatable member separating said right and left hand screw threads, said plate having a depression in which said annular ribs engage and a handle attached to one end of said rotatable member.

2. A clamp for slidable closures comprising a body plate adapted to be fastened to a member along which the closures are adapted to slide, an upstanding jaw fixed on said body plate on opposite sides of which closures are adapted to be clamped said plate having recesses on opposite sides of the jaw, movable jaws on opposite sides of the fixed jaw and having reduced portions extending downwardly through and slidably engaging in said recesses, said jaws being longer than the recesses and providing over-hanging portions slidably engaging the upper side of the plate, inwardly extending arcuate flanges on the lower portions of the jaws, 55 ribs on the upper sides of said flanges said jaws having openings in the lower portions thereof, a member rotatable in said openings and projecting outwardly at its ends from said jaws, said member having right and left hand screw threads engaging the ribs on said arcuate flanges, tracks extending beneath and supported by the said plate and flanges on the upper ends of the arcuate flanges slidably engaging said tracks.

ANTON J. KOPP.
